(57) **CLAIM**

The ornamental design for a tape dispensing cat, as shown and described.

DESCRIPTION

FIG. 1 is an isometric perspective view of a tape dispensing cat;

FIG. 2 is a right side elevation view thereof;

FIG. 3 is a left side elevation view thereof;

FIG. 4 is a front perspective view thereof;

FIG. 5 is a rear perspective view thereof;

FIG. 6 is a top plan view thereof; and,

FIG. 7 is a bottom plan view thereof.

The broken lines shown in the drawings represent portions of the tape dispensing cat that form no part of the claimed design.
